UNITED STATES PATENT OFFICE.

GIFFORD E. BLAYLOCK, OF BALTIMORE, MARYLAND.

BLOW-OUT PATCH.

Application filed June 20, 1927. Serial No. 200,149.

The object of this invention is to provide a tire patch which may be readily and effectively applied and held in place.

The invention consists of a patch piece 5 provided with an adhesive attaching strip having self-adhering wings, which are capable of being stuck together and then folded over and stuck to the patch piece, as I will proceed now more fully to explain and finally claim.

In the accompanying drawings illustrating the invention, in the several figures of which like parts are similarly designated, Figure 1 is a perspective view with the patch 15 open. Fig. 2 is a perspective view with the wings united by a double fold. Fig. 3 is a similar view with the wings united by a single fold.

The patch piece 1 may be of any appropriate material and size, of substantially the form and proportion shown in Fig. 1. The inner side or face of this patch piece is made of inert material or provided with an inert substance so as not to adhere to the 25 body which it surrounds, but the outer face is provided with an adhesive or tacky substance so that the patch piece when applied will adhere to the casing or shoe. To this piece is attached the strip 2, of strong material, such as canvas or duck, coated or saturated with an adhesive or tacky substance in such way that such substance appears on both sides of the material. The strip 2 is of greater length than the width 35 or circumference of the patch piece 1, so as to provide wings 3 standing off from the adjacent edges of the piece 1.

When the patch piece 1 is applied in use, it is secured in place firmly by means of the

strip 2 having its wings brought together 40 and caused to adhere by means of their tacky surfaces, and then this joint may be further secured by folding over upon themselves the thus adhered wings, each fold separately adhering and the final fold turned over and 45 adhered to the body of the strip, as shown in Fig. 2. But, as shown in Fig. 3, the adhered wings may be folded over in a single fold and then caused to adhere to the body of the strip.

The strip 2 thus provides a self-adhering and self-locking member for the patch piece, and consequently the patch piece may be readily applied.

Variations in the details of construction 55 and arrangement are permissible within the principle of the invention and the scope of the claims following.

What I claim is:—

1. A patch piece for tires, having an application strip provided with an adhesive substance on both of its sides, the ends of the strip forming wings which when in position of use are closely united by pressing their adjacent tacky surfaces together and 60 then folding over the thus adhered wings and causing them to adhere to the body of the strip.

2. A blowout patch, of the character described, in which the inner surface is non-adhesive so as not to adhere to the inner tube and the outer surface is adhesive so as to adhere to the outer casing, said patch having a self-adhering application strip 70 provided with self-locking extensions.

In testimony whereof I have hereunto set my hand this 20th day of June, A. D. 1927.

GIFFORD E. BLAYLOCK.
